United States Patent Office.

FRANKLIN BABCOCK AND FREDERICK BABCOCK, OF MIDDLETOWN, CONNECTICUT.

Letters Patent No. 82,581, dated September 29, 1868.

IMPROVEMENT IN DOOR-LATCH.

The Schedule referred to in these Letters Patent and making part of the same.

TO ALL WHOM IT MAY CONCERN:

Be it known that we, FRANKLIN BABCOCK and FREDERICK BABCOCK, of Middletown, county of Middlesex, and State of Connecticut, have invented a new and improved Door-Latch; and we do hereby declare that the following is a full and exact description of the same, reference being had to the accompanying drawings.

Figure 1 is a perspective view,

Figure 2 is a sectional view, and

Figure 3 an end view of the door-latch; and

Figure 4 is a perspective view,

Figure 5 is a sectional view, and

Figure 6 an end view of the bolt-receiver.

To enable others to understand the use and construction of our invention, we will proceed to describe it.

We make a cylindrical shell or case, figs. 1, 2, and 3, with projections or arms *d d*, fig. 1, extending a proper distance from the shell, to provide a bearing for the cam *a*, the cam to be operated by means of a knob-spindle. The bolt *b* is connected to the cam *a* by a chain or links, *e e*, so that by turning the knob *b* the bolt *b* is drawn from the receiver, figs. 4, 5, and 6, and is thrown back by the spring *c*.

The shell has a screw-thread on its outer periphery to secure it firmly in its place without the use of detached screws. It also possesses the advantage of being applied with greater facility than ordinary door-latches, requiring simply the boring of a hole of proper dimensions, without removing the wood about the spindle, which often prevents the proper securing of the knob-plates for want of sufficient thickness of wood to hold the screws.

The receiver, figs. 4, 5, and 6, is made in the same manner as the shell of the latch, having a screw-thread on its outer periphery, to secure it firmly in its place, and the receiver-plate *f* being secured to the case by the flange on the shell.

The novelty of our invention is its easy application, durability, and compactness.

We are aware that a latch, with coil-spring around, and operated by chains, connecting with a revolving socket, is not new. The cam *a* used by us is provided with a circumferential flange in its centre, and is secured in the concave ends of the case, thereby dispensing with journals or axes. The shell or case is threaded as shown.

What we claim, is—

The revolving flanged cam *a*, when attached in the concaved ends of the case *A*, which is provided with a screw-thread on its exterior, all constructed to operate as specified.

FRANKLIN BABCOCK.
FREDERICK BABCOCK.
